UNITED STATES PATENT OFFICE.

ALBERT HOLTZ, OF FAIRBURY, NEBRASKA, ASSIGNOR OF ONE-HALF TO
ALBERT D. MCCULLOUGH, OF FAIRBURY, NEBRASKA.

TWO-ROW DISK CULTIVATOR.

SPECIFICATION forming part of Letters Patent No. 728,798, dated May 19, 1903.

Application filed October 20, 1902. Serial No. 128,019. (No model.)

To all whom it may concern:

Be it known that I, ALBERT HOLTZ, residing at Fairbury, in the county of Jefferson and State of Nebraska, have invented certain useful Improvements in Two-Row Disk Cultivators; and I do hereby declare that the following is a full, clear, and exact description of the invention, such as will enable others skilled in the art to which it appertains to make and use the same, reference being had to the accompanying drawings, which form a part of this specification.

This invention relates to a new and useful improvement in two-row disk cultivators.

The aim of my invention is to provide a cultivator by means of which two rows may be simultaneously cultivated, and embodies certain novel features, as will be described more fully hereinafter and finally pointed out in the claim.

In the accompanying drawings I have shown in Figure 1 a top view with portions removed of a cultivator embodying my invention. Fig. 2 shows a side elevation of my two-row disk cultivator with portions removed on line $\alpha\alpha$ of Fig. 1. Fig. 3 discloses a top view of one of the pivotally-held disk-holders. Fig. 4 discloses a detail of one of the disk-shaft holders. Fig. 5 shows an end view disclosing the device used in raising and lowering the disk-holders. Fig. 6 shows a detached enlarged detail of one of the disk-holders, showing the connected disk-shaft, while Fig. 7 shows the arrangement of one of the equalizers used in connection with my invention.

In connection with my two-row disk cultivator I employ a straight bar B, preferably of angle-iron, and an adjacent bar C, preferably of channel-iron, as is clearly shown in Fig. 2. These bars form the main transverse supporting members of the frame used in connection with my two-row disk cultivator. Extending from the channel-bar C and being suitably secured to the forward frame member B is an ordinary tongue D, as is shown in Fig. 1. Extending from and secured to the horizontal portion of the forward frame member B are the end longitudinally held and slotted frame members A, and intermediate of these end members A are held the

counterpart slotted frame members A'. (Shown in the top view in Fig. 1.) These longitudinally held and slotted frame members A and A' are secured to the transverse frame members B and C by means of suitable rivets 1, and each of these frame members is further provided with the slots a. (Shown in Fig. 1.)

Uniting each end frame member A and the adjacent frame member A' upon the opposite ends is an arched bar H, and these two arched bars H, one of which is shown in detail in Fig. 5, are again united by means of the angle-iron intermediate frame member B', (shown in Figs. 1 and 5,) these frame members H and B' being secured by suitable rivets 1.

Extending upward and rearward from the intermediate frame member B' is a seat-bar 30, provided with the seat 31, as is shown in Fig. 1. In Fig. 2 this seat and its connected bar are eliminated.

The frame members A and A' are preferably made of angle-iron and are provided with the bolts b, used in sets of twos, each set of bolts b supporting a suitable bearing 2, as is shown in Fig. 4, so that these bearings 2 may be shifted backward or forward by means of the set-bolts b. Held within each set of bearings 2 is a shaft 2', and revolubly held upon these shafts 2' and laterally sliding upon the same are the disk-holding sleeves F, to which are secured the disks E in sets of twos. These disks face one another, as is disclosed in Fig. 1. Loosely surrounding these disk-holding sleeves F is a pivotally-held disk-holder comprising the bearing 4, the forward-extending ear 3, and the trailing arms 5, as is shown in Figs. 1, 2, and 6. These disk-holders are preferably made of sheet metal, and the trailing arms 5 are bent at right angles to the bearing portion 4, as will be understood in referring to Fig. 6, and these bearing-arms are provided with the perforations z', adapted to receive the bolts of suitable disk and shovel holders, as shown in Figs. 1 and 2.

In order to form a complete bearing, the disk-holders are provided below with a bearing portion 4', suitably secured, as is shown in Fig. 6, and from the forward end 3 of these holders extends a suitable ring 6, as shown. These sleeves F revolve freely upon the shafts

2', held within the bearings or holders 2, while loosely working upon the sleeve F again between each set of disks is a pivotally-held disk-holder provided with two outwardly-spreading trailing arms, as shown.

Secured to the forward frame member B are two pins 9, each pin adjustably holding a set of equalizer-bars 10, as shown in Fig. 7, provided with suitable perforations, so that the same may be adjustably secured to the pins 9, and secured to each set of equalizer-bars 10 is a chain 7, united, by means of the rings 6 and 8, to the disk-holders and the equalizer-bars 10, as is shown in Fig. 1. The remaining end of each equalizer-bar 10 is provided with a sheave 12, over which extends a chain N', secured to the eyebolts 13 of the singletrees 14. (Shown in Fig. 1.)

Secured to the trailing arms 5 are the forward bearings 40, receiving the stems 41 of the cutter-disks 42, these cutter-disks being used in sets of twos, and near the end each trailing arm 5 is further provided with a bearing 43, adapted to receive the stem 45 of a suitable shovel 46. In this it will be noticed that the main frame of my cultivator is supported by means of the usual wheel-disks E and that I provide two pivotally-held disk-holders, each being provided with two cutter-disks and two trailing shovels.

In order to raise and lower the cutter-disks and cultivator-shovels in going and coming to and from the field, I provide the standards N, supporting the rock-shafts 32, each provided at one end with an enlargement 30' to prevent the lateral displacement of this shaft, while at the opposite end each rock-shaft 32 is provided with an ordinary lever 33, provided with a thumb-latch e, working in conjunction with an ordinary notched sector, as is shown in Fig. 5 and as is usual in the construction of agricultural implements. These notched sectors are secured by means of the plates 37, forming a part of the notched sectors, which plates by means of the bolts

38 are secured to the intermediate frame member B'. It will be noticed that these levers 33, secured to the rock-shafts 32, are placed to the right and left and adjacent the operator's seat 31. Extending from each rock-shaft 32, as shown in Fig. 5, is a chain 6', and these chains 6' are secured to the rings 8', as shown in Fig. 3, secured to the transverse bars 5', forming a part of each pivotally-held disk-holder, as shown.

Now, having thus described my said invention, what I claim as new, and desire to secure by United States Letters Patent, is—

In a two-row disk cultivator the combination with a rectangular supporting-frame, of a set of arched bars secured upon opposite and rear ends of the frame, of two equalizer-bars pivotally and adjustably secured to the forward end of said supporting-frame, a sheave within each equalizer-bar, a chain 65 passing over each sheave and provided at each end with a singletree, a chain extending rearward from each equalizer-bar, bearings adjustably secured in sets of twos upon opposite sides to aforesaid supporting-frame, a 70 shaft held by each set of bearings, a sleeve revolvably held upon each shaft, supporting wheel-disks secured to each sleeve, a pivotally-held disk-holder secured to each sleeve adjacent said supporting disk-wheels, the 75 forward end of each pivotally-held disk-holder being secured to the aforesaid chain extending from each equalizer-bar, cutter-disks secured in sets of twos to each of said disk-holders, cultivator-shovels secured to each of 80 aforesaid disk-holders, and rock-shafts secured to said disk-holder as and for the purpose set forth.

In testimony whereof I affix my signature in presence of two witnesses.

ALBERT HOLTZ.
